A. CLEMENSEN

SAW CLAMP

Filed Oct. 21, 1926

UNITED STATES PATENT OFFICE.

AXEL CLEMENSEN, OF CHICAGO, ILLINOIS.

SAW CLAMP.

Application filed October 21, 1926. Serial No. 143,142.

This invention relates to an improved clamping block for clamping and holding a plurality of saws in spaced relation to permit the saws to be conveniently held in place or carried within a carpenter's tool box or in any other suitable container having clamping devices of this invention mounted therein.

It is an object of this invention to provide 10 a saw clamp adapted to hold a plurality of saws in parallel spaced relation.

It is also an object of this invention to provide a slotted resilient block with a clamping means for holding saw blades within 15 the slots in spaced relation against shifting.

It is also an object of this invention to provide split clamping devices adapted to be secured in position within the cover or 20 any other suitable part of a tool box in a position to permit a plurality of saws to be engaged in the clamping devices and frictionally held therein in clamped relation by suitable clamping means.

25 It is an important object of this invention to provide an improved slotted clamp adapted to receive and hold a plurality of saw blades in spaced relation by means of a suitable set screw mechanism adapted to 30 compress the slotted clamp to hold the saws frictionally clamped within the slots of the device.

Other and further important objects of 35 this invention will be apparent from the disclosures in the specification and the accompanying drawings.

This invention (in a preferred form) is illustrated in the drawings and hereinafter more fully described.

40 On the drawings:

Figure 1 is a perspective view of a carpenter's tool box with the cover in open position and equipped with a pair of saw clamps embodying the principles of this invention.

Figure 2 is an enlarged longitudinal section of a saw clamp taken on line II-II of Figure 1 showing a portion of the tool box cover.

50 Figure 3 is a top plan view of the saw clamp illustrated in Figure 2.

Figure 4 is a longitudinal section similar

to Figure 2 but disclosing a modified form of saw clamp secured in position within a tool box cover.

55

Figure 5 is a top plan view of the saw clamp as illustrated in Figure 4.

As shown on the drawings:

The reference numeral 1 indicates a carpenter's tool box or other suitable container 60 provided with a hinged cover 2. Rigidly mounted within the tool box cover 2 are a pair of saw clamps embodying the principles of this invention.

The improved saw clamp comprises a 65 block 3 constructed of wood or other suitable material provided with a plurality of parallel slots 4 which extend transversely from the top of the block downwardly to within a short distance of the lower end of the 70 block. The lower end of the front face of the block is provided with a notch 5 to receive the head 6 of a retaining screw bolt 7 which projects through a passage in the lower end of the block and extends through 75 a washer sleeve 8 engaged in an aperture provided in the cover 2. The bolt 7 thus acts to hold the block 3 seated transversely within the tool box cover 2 with the back of the block abutting the inner surface of the main 80 wall of the cover. The upper end of the rear wall of the block is notched to receive a metal plate 9 having forwardly directed apertured ears or lugs 10. The plate 9 is provided with a lower countersunk aperture 85 adapted to receive a retaining screw 11 for rigidly holding the plate 9 secured to the block. The plate 9 extends above the upper edge of the block 3 and is provided with an upper aperture adapted to receive a retaining 90 screw bolt 12 which projects through a washer sleeve 13 within the tool box cover

95 a to hold the upper end of the block 3 rigidly secured in place. The lugs 10 of the back plate 9 project forwardly on opposite sides 100 of the upper portion of the block and are spaced from the block a distance sufficient to permit the yoke pins 14 to project outwardly therethrough. The yoke pins 14 are formed at right angles to the ends of a pair of yoke arms 15, the outer ends of which are integrally connected by a yoke cross bar or plate 16. The yoke cross bar 16 is provided with a threaded aperture

in which a clamping screw 17 is adjustably threaded. Integrally formed on the outer end of the clamping screw 17 is a flat head or finger piece 18 to permit the screw to 5 be conveniently rotated. Rotatably mounted on the inner end of the screw 17 is a clamping head or disk 19 adapted to seat against the upper portion of the front surface of the clamping block 3 when the clamping screw 10 17 is tightened to cause the arms or blades of the slotted block to be compressed against one another in clamping relation so that saw blades or other similar tools or instruments disposed within the slots 4 will be 15 frictionally clamped in position against sliding or shifting below the yoke arms 15 which serve as a stop to hold the saw blades from being lifted out of the block when the clamp screw is set.

20 With a pair of improved saw clamps mounted within the cover 2 of the tool box it will be noted that by loosening the clamping screws 17 by means of the flat or wing heads 18 that the clamping heads 19 are released or 25 moved out of contact with the block thereby permitting the yoke members 15-16 to be pivotally swung upwardly on the pivot pins 14 to open the upper ends of the slotted blocks. With the yokes in open position a 30 plurality of saws may be placed within two clamp blocks with the handles of the saws alternately positioned in opposite ends of the cover 2 with the saw blades extending from one block to the other. As illustrated 35 in the drawings it will be noted that the blocks are of a capacity sufficient to hold four saws in parallel relation. The saws when in position are adapted to seat in the lower ends of the slots 4 after which the 40 yokes 15-16 are swung downwardly over the heads of the blocks and the clamping screws are turned by means of the flat heads 18 until the clamping heads 19 of said screws rigidly clamp against the upper end of the 45 block thereby causing the tines or blades of the slotted blocks to be compressed and clamped against the saw blades thereby rigidly holding the saws in position within the tool box cover against sliding or shifting. With the clamping screws set as described the cover may be swung upwardly 50 into closed position and the tool box closed with the saws securely held in their set position of adjustment within the tool box cover.

55 Figures 4 and 5 disclose a modified form of saw clamp adapted to be positioned within a tool box cover 2 or within any other suitable container or mounting. The modified form of saw clamp comprises a block 20 made of wood or other suitable material and provided with a plurality of longitudinal slots 21 positioned transversely of the block and running from the upper end of the block downwardly to within a short distance of the lower end of the block, thereby 60 dividing the block into a plurality of resilient tines or blades. Mounted against the rear surface or back of the block 20 is a metal back plate 22 provided with a lower aperture through which a retaining screw 70 or bolt 23 projects. The bolt 23 projects through an opening in the lower end of the block 20 and then passes through an opening in the lower end of a metal front plate 24. Adjustably engaged on the projecting 75 end of the retaining bolt 23 is a butterfly or wing nut 25 adapted to be tightened to cause the end of a pin or spike 26 to be forced into the wood forming the main or back plate of the tool box cover 2, as illustrated in Figure 4. The pin or spike 26 is integrally formed on the lower end of the metal face plate 24 and is bent at right angles thereto to project rearwardly through a 80 groove 27 formed in the bottom of the clamp block 20. The upper end of the metal face plate 24 extends above the upper end of the block 20 and is notched to receive the threaded end of a clamping screw or bolt 28 removably seated therein. One end of the clamping bolt 28 is pivoted at 29 to the upper projecting end of the metal back plate 22 of the device. The upper portion of the metal back plate 22 is also provided with an aperture to receive a retaining bolt 30 which projects through an opening in the cover 2 to hold the upper portion of the saw clamped secure to the cover 2. Adjustably threaded on the outer projecting end of the clamping bolt 28 is a butterfly or wing nut 90 31 adapted to be threaded on the end of the bolt 28 against the upper notched end of the metal face plate 24, thereby causing the face plate to be moved rearwardly towards the back plate to compress the blades of the block 95 20 tightly against one another so that saw blades or other similar tools positioned within the slots 21 of the block will be tightly compressed and held in spaced relation against shifting or sliding. One or more of the improved saw clamps, as illustrated in Figure 4, may be positioned within a tool box cover 2 or upon any other suitable mounting to permit saws or similar devices 100 to be held in spaced parallel clamped relation against movement, particularly in containers such as carpenter's tool boxes which are usually moved around considerably or shipped from one job to another.

105 The use of the improved saw clamps is believed self evident from the description hereinbefore given and affords an efficient means for holding the blades of saws in position in order to protect the cutting edges or teeth of the saws against damage.

110 I am aware that many changes may be made, and numerous details of construction may be varied through a wide range without departing from the principles of this invention, and I therefore do not purpose 115 120 125 130 135

limiting the patent granted hereon, otherwise than necessitated by the prior art.

I claim as my invention:

1. A saw clamp comprising a block having a plurality of transverse longitudinal slots therein extending from one end of the block to within a short distance of the opposite end and adapted to receive a plurality of saws or similar instruments in spaced parallel relation, and clamping means pivotally mounted on the upper slotted end of the block adapted to be swung downwardly over the block and then adjusted to compress the slotted block to rigidly hold the saws clamped in position against movement.
2. A saw holding device of the class described comprising a longitudinally slotted block, a member pivoted thereon and clamping means adjustably engaged on said member adapted to compress the slotted block to hold the saws in place.
3. A saw holder of the class described comprising a block provided with a plurality of parallel slots dividing the block into resilient blades, a mounting plate secured to one end of the block, apertured lugs integrally formed on said mounting plate at right angles thereto, a yoke member pivotally mounted in said lugs adapted to be swung downwardly over the upper slotted end of the block, a flat headed screw adjustably carried by the yoke member, and a clamping head rotatably mounted on said screw adapted to be pressed against the upper end of the slotted block when the

screw is tightened to cause the blades of the slotted block to be compressed toward one another to rigidly clamp the saws in position against movement.

4. An instrument holder of the class described comprising a block provided with a plurality of spaced slots adapted to receive the blades of instruments, an apertured mounting plate secured to one end of the block, a yoke member pivoted on said mounting plate adapted to be swung over the slotted end of said block, and adjustable clamping means carried by said yoke adapted to be adjusted to cause the slotted block to be compressed to rigidly hold the instrument blades clamped in position against movement with respect to the block.

5. An instrument holder comprising a longitudinally slotted block, retaining means for holding one end of the block secured in place, an apertured plate, means for securing said plate to the block, a yoke member pivotally mounted on said plate and adapted to be swung over the upper slotted end of said block, a screw adjustably carried by said yoke, and a head movably mounted on said screw adapted to be moved into clamping relation with said block to compress the same and rigidly hold the instrument blades clamped in position against movement with respect to the block.

In testimony whereof I have hereunto subscribed my name.

AXEL CLEMENSEN.
